GORSEY F. ASBURY, OF WASHINGTON, DISTRICT OF COLUMBIA, ASSIGNOR TO UNITED STATES ORDNANCE COMPANY, OF WASHINGTON, DISTRICT OF COLUMBIA, A CORPORATION OF VIRGINIA.

BREECH CLOSURE.

1,410,524.

Specification of Letters Patent. Patented Mar. 21, 1922.

Application filed October 30, 1918. Serial No. 260,389.

To all whom it may concern:

Be it known that I, DORSEY F. ASBURY, a citizen of the United States, residing at Washington, District of Columbia, have invented certain new and useful Improvements in Breech Closures; and I do hereby declare the following to be a full, clear, and exact description of the invention, such as will enable those skilled in the art to which it appertains to make and use the same.

My invention relates to breech closures and is particularly adapted for application to those breech closures whose opening and closing movements are affected automatically, yet certain elementary parts of my invention are applicable to those closures wherein the complete operation of opening and closing is not effected automatically.

It is the object of my invention to provide means independent of elasticity and resiliency for utilizing motion imparted to the breech closure by discharge of the gun to open and close the breech closure and thereby eliminate the use of spring elements of any kind as a positive actuating medium in the operation of automatically opening and closing the gun breech. It will be observed, however, that when I refer to imparting motion to a breech closure by discharge of the gun, it is my intention to include within the scope of such expression either a structure wherein the breech closing element proper, such as a breech bolt or screw block or wedge block, is so moved or a structure wherein some member operatively associated with the breech closing element proper is moved; my invention serving in either case to utilize such motion to open and close the breech closure independent of both elasticity and resiliency.

Further objects of my invention are to provide means independent of both elasticity and resiliency for utilizing energy due to discharge of the gun to open and close the breech closure; to provide means for automatically utilizing only kinetic energy to produce all operations of the breech closure; to provide a structure wherein only moving mass set in motion by the discharge of the gun is used to effect the full operation of the breech closure; to provide means automatically utilizing moving mass to change opening movement of the breech closure to closing movement; to provide means independent of both elasticity and re-

siliency for changing the opening movement of the breech closure to closing movement; to provide means independent of both elasticity and resiliency for translating the energy stored in the opening breech closure to energy acting to close the breech closure; to provide rotatable means for automatically changing the opening movement of the breech closure to closing movement; to provide rotatable means for translating the energy stored in the opening breech closure to energy to close the breech closure; to provide means movable one way to change the opening movement of the breech closure to closing movement, and moving oppositely to effect the next change of breech closure opening movement to closing movement; to provide means independent of both elasticity and resiliency for utilizing stored energy resulting from the opening of the breech closure to retard said closure's opening movement as it nears full open position and then to arrest said opening movement; to provide means for translating stored energy resulting from opening of the breech closure to energy acting to close the breech closure and operating to delay the closing movement; to provide movable means operating while moving to hold the breech closure in open position; to provide a cam device for translating stored energy resulting from opening of the breech closure to energy acting to close the breech closure; to provide a cam device for translating opening movement of the breech closure to closing movement; to provide a cam device for utilizing stored energy resulting from opening of the breech closure to initiate closing of the breech closure; to provide a longitudinally movable breech closure in combination with non-elastic means for translating the opening movement thereof to closing movement; to provide a longitudinally movable breech closure and a cam device in combination therewith for translating opening movement thereof to closing movement; and to provide a simple and novel structure through the instrumentality of which I am enabled to attain in a practical way the various fundamental objects of my invention herefore referred to.

I will describe my invention as applied to 11

a gun whose breech closure embodies a longitudinally reciprocating breech bolt, but it will be understood that my invention is equally applicable to other forms of breech closures, such as screw blocks and wedge blocks, and that the invention is susceptible to wide variations in form without in the least departing from the scope of the claims; the drawings and description forming a part hereof being merely illustrative of one method of carrying the invention into practice.

In describing my invention reference will be had to the accompanying drawings wherein like characters of reference denote corresponding parts in the several views, and in which—

Fig. 1 is a vertical section of a breech closure embodying my invention, the closure being shown in its home or locked position;

Fig. 2, a section on the line 2—2 of Fig. 1;

Fig. 3, a section on the line 3—3 of Fig. 1;

Fig. 4, a section on the line 4—4 of Fig. 1;

Fig. 5, a horizontal section of what is shown in Fig. 1, looking down;

Fig. 6, a horizontal section of what is shown in Fig. 1 looking up;

Fig. 7, a bottom view of what is shown in Fig. 1; and

Fig. 8, a sectional view of a fragment of the breech bolt showing the combined extractor and ejector.

Referring to the drawings 10 indicates a recoil mount and 11 the gun arranged to slide in said mount during recoil and counter recoil, said gun being connected with a suitable recoil brake (not shown) by a rod 12 all as is well known. The gun 11 is provided at its rear end with a breech chamber 13 in which is mounted for reciprocation to open and closed positions a breech closure A. This closure comprises a bolt 14 having an intermediate reduced portion 15 on which is rotatably mounted a member 16 having locking lugs 17 cooperating with locking lugs 18 on the gun 11 to secure the closure in closed position, the lugs being disaligned by rotation of the member to unlock the closure. Also provided on the member 16 is a handle 19 one purpose of which is to afford means for the manual operation of the breech closure when desired. Mounted on this handle 19 are outer and inner cam followers 20 and 21 for a purpose that will presently appear.

The mount 10 is provided with a cut-away portion 23 opening through its rear and having a part of the wall thereof shaped to form a cam 24 with which the cam follower 20 is adapted to cooperate during recoil to impart rotative movement to the member 16. The gun 11 is provided with a slot 25 open-

ing through its rear and extending longitudinally of the gun except at its forward end where it curves laterally to form a cam surface 26 with which the cam follower 21 coacts, immediately following the coaction 70 of the cam 24 and the follower 20, to change the rotative movement of the member to rearward longitudinal movement and thereby impart opening movement to the entire breech closure. To change this opening 75 movement of the breech closure to closing movement I resort to the following structure. The rear end of the bolt 14 is further reduced at 27 and rotatably mounted on said reduced portion is a translating member 28. 80 This member I provide with a cam groove B the end portions 29 and 30 of which are substantially parallel and open through the rear end of the member to permit, during opening and closing of the breech closure, 85 the entrance and exit of a cam follower 31 mounted on the gun as will hereinafter appear. The portions 29 and 30 of the groove B as they extend forward are curved away from each other to form cam surfaces 32 and 90 33, said groove being completed by a circumscribing portion 34. To hold the portions 29 and 30 of the groove B in workable alinement with the cam follower 31, except when the member 28 is rotating, I provide 95 said member with longitudinal grooves 35 and 36 which are adapted to successively receive a longitudinal rib 37 carried by the gun and projecting into the breech chamber 13, said rib being disposed in the groove 35 100 to hold the portion 29 of the groove B in workable alinement with the cam follower 31 and in the groove 36 to hold the portion 30 of the groove B in workable alinement with said cam follower.

105

The members 16 and 28 of the breech closure are separated by an anti-friction bearing C composed of two rings 38 and 39 provided with opposed races 40 in which anti-friction balls 41 are located.

110

The bolt 14 carries an extractor 42 which also serves as an ejector, the ejection action thereof being produced by a cam surface 43 formed in the base of a groove 44, the latter being formed in and extending longitudinally of the gun. It will be obvious upon reference to Fig. 5 that during the opening movement of the bolt 14 the free end of the extractor 42 will be forced sharply toward the bolt and serve to eject the cartridge case 120 through the opening 45 provided in the gun 11 to permit such ejection. It will be observed that the extractor 42 is constantly disposed in the groove 44 and thereby serves to hold the bolt 14 against axial rotation. The 125 cartridges are fed to the gun by gravity or a spring from a magazine 46 provided on the mount, said cartridges being delivered from the magazine to the gun through an opening 47 in a manner that will be best understood 130

from the description of the operation of the breech closure which follows.

Assume that the gun is loaded and that a supply of cartridges is present in the magazine 46. With the parts in the position shown in the several views the charge of the gun is fired through the medium of any desirable firing device mounted in the bolt 14 and not illustrated in this instance as such firing device forms no part of the invention. As soon as the gun is fired the latter recoils. During such recoil no change in the positions of the parts of the breech closure with respect to the gun takes place until the cam follower 20 coacts with the cam 24. This coaction sharply rotates the member 16, and during this rotation of said member the lugs 17 are moved out of alignment with the lugs 18 and the cam follower 21 and the cam 26 coact to change the rotative movement of the member 16 to longitudinal movement and after this change takes place the cam follower 21 moves to the rear in the slot 25. Likewise the entire breech closure moves to the rear under the influence of the energy imparted thereto by the longitudinal movement of the member 16. As the translating member 28 moves to the rear the cam follower 31 enters the portion 29 of the groove B and eventually coacts with the cam 32 to rotate the member 28. During the continued rotation of the member 28 the cam follower moves through the circumscribing portion 34 of the groove B and then coacts with the cam 33, such coaction serving to change the rotary movement of the member 28 to forward longitudinal movement and such forward longitudinal movement is of course imparted to the entire breech closure, the cam follower 31 finally leaving groove B through the portion 30 and the rib 37 enters the groove 36 to hold the member 28 against further rotation and to maintain the portion 30 of the groove B in workable alignment with the cam follower 31 for the next operation. As the breech closure moves home the cam follower 21 again coacts with the cam 26 to impart locking rotation to the member 16. By noting the position of the cam 43 it will be obvious that the ejection of the empty cartridge case takes place before the opening 47 registers with the magazine 46 and that when such registration takes place the bolt 14 is substantially fully retracted so that the lowermost cartridge in the magazine can move down by gravity into position to be forced into the cartridge chamber of the gun barrel by the closing of the bolt. It will also be observed that during one complete operation of the breech closure the member 28 rotates in one direction and in the opposite direction during the next complete operation of the breech closure, the portions 29 and 30 of the groove

B each successively constituting entrances and exits for the cam follower 31 with respect to successive operations of the breech closure. Furthermore, it will be observed that the cams 32 and 33 serve as means for retarding opening movement of the breech closure and such a construction can be utilized in closures in which the closing operation is not effected automatically. Again, these cams 32 and 33 in connection with the circumscribing portion 34 serve as a means for utilizing energy of an opening breech closure to arrest the opening movement thereof and such structure can readily be utilized in breech closures which are not fully automatic. Again, the provision of the circumscribing portion 34 of the groove B serves as a means for delaying the closing movement of the breech closure and also serves as a means of utilizing a moving element to hold the breech closure in open position. The interval of time between the completion of the opening movement of the bolt and the initiation of the closing movement can be increased or decreased by lengthening or shortening the circumscribing portion 34 of the groove B.

I claim:

1. In a gun, a breech closure movable bodily to open and closed positions, and means operated by discharge to energize the mass of the closure, said energized mass reacting bodily against the gun to produce the opening and closing movements of the closure.
2. In a gun, a breech closure movable bodily to open and closed positions, and means operated by discharge to energize the mass of the closure, said energized mass reacting bodily against the gun to change opening movement of the closure to closing movement.
3. In a gun, a bodily movable breech closure, means operated by discharge to initiate movement of the breech closure relatively to the gun, and means fixed relatively to the gun coacting only with the bodily moving mass of the breech closure to complete the cycle of operation of said closure.
4. In a recoil gun, a bodily longitudinally movable breech closure including rotatable members, and non-elastic means having portions fixed relatively to a recoiling part and non-recording part of the gun respectively and coacting with said members upon discharge of the gun to produce all movements of the breech closure relative to the gun.
5. In a gun, a breech closure, and rotatable means carried by the closure and reacting against the gun to automatically change the opening movement of the breech closure to closing movement.
6. In a gun, a breech closure, a rotatable member carried by the breech closure for

translating the energy stored in the opening breech closure to energy to close the breech closure.

7. In a gun, a breech closure movable bodily to open and closed positions, a cam element fixed relatively to the gun, and a cam element on the breech closure coacting with the element on the gun to change opening movement of the closure to closing movement.

8. In a gun, a breech closure movable to open and closed positions, a cam on the closure, and a cam follower fixed relatively to the gun and coacting with the cam on the closure to change opening movement thereof to closing movement.

9. In a gun, a breech closure movable to open and closed positions, cam elements on the gun having a fixed relation thereto, and cam elements on the breech closure coacting respectively under the influence of energy delivered from the closure with the cam elements on the gun to open and close the breech closure, and means for energizing the closure.

10. In a gun, a breech closure, and means carried by the closure movable one way to change the opening movement of the breech closure to closing movement, and moving oppositely to effect the next change of breech closure opening movement to closing movement.

11. In a gun, a breech closure, and a non-elastic movable member carried by the breech closure and operated by opening movement of the breech closure to translate said movement to closing movement.

12. In a gun, a longitudinally movable breech closure, and a non-elastic member carried by the breech closure and movable relatively thereto for translating the opening movement thereof to closing movement.

13. In a gun, a breech bolt, a rotatable member carried by the bolt for changing opening movement thereof to closing movement, and an anti-friction bearing between the bolt and member.

14. In a gun, a breech bolt, a rotatable member for opening the bolt, a second rotatable member for changing opening movement of the bolt to closing movement, and an anti-friction bearing between said members.

15. In a gun, a breech bolt, a rotatable member carried by the bolt for opening the latter, a second rotatable member carried by the bolt for changing opening movement thereof to closing movement, and an anti-friction bearing between said members.

16. In a gun, a recoil mount, a longitudinally movable breech bolt, a rotatable unlocking member carried by the bolt, a cam device between the member and mount for rotating the member, and a second cam device between the member and gun for trans-

lating the unlocking movement of the member to movement to open the bolt.

17. In a gun, a breech closure, a pair of cams, and a pair of cam followers coacting with the cams respectively and successively to unlock the breech closure and then translate the unlocking movement thereof to opening movement.

18. In a gun, a recoil mount, a breech closure, a cam on the mount, a cam on the gun, and a pair of cam followers carried by the closure and coacting respectively and successively with the cam on the mount and the cam on the gun to unlock the breech closure and then translate the unlocking movement thereof to opening movement.

19. In a gun, a recoil mount, a breech closure having a rotatable locking member, a handle on said member, a cam on the mount, a cam on the gun, and a pair of cam followers mounted on said handle and coacting respectively and successively with the cam on the mount and the cam on the gun to impart unlocking rotation to the member and then translate said rotation to movement to open the breech closure.

20. In a gun, a breech closure having a rotatable locking member, a handle on said member, a pair of cams, and a pair of cam followers mounted on said handle and coacting respectively and successively with the cams to impart unlocking rotation to the member and then translate said rotation to movement to open the breech closure.

21. In a gun, a longitudinally movable breech bolt, a rotatable member carried by the bolt, and a cam device between the member and gun for translating opening movement of the bolt to closing movement.

22. In a gun, a longitudinally movable breech bolt, a rotatable member carried by the bolt, and a cam and cam follower one of which is on the gun and the other on the member, for translating opening movement of the bolt to closing movement.

23. In a gun, a longitudinally movable breech bolt, a rotatable member carried by the bolt, a cam on the member, and a cam follower on the gun coacting with the cam on the member to translate opening movement of the bolt to closing movement.

24. In a recoil gun, a movable breech closure, means carried by the closure reacting directly against a recoiling part of the gun when said closure is energized to open, close and lock the closure, and means for energizing the closure.

25. In a gun, a movable breech closure, means for producing relative movement of the closure to the gun to energize said closure, and means whereby said closure is thereafter removed solely by its own kinetic energy to produce its other movements relative to the gun.

26. In a gun, a movable breech closure, means for producing relative movement of the closure to the gun to energize said closure, and cam means operated thereafter 5 solely by the energy initially stored in the closure to produce the other movements of the closure relative to the gun.

In testimony whereof I affix my signature in the presence of two witnesses.

Certificate of Correction.

It is hereby certified that in Letters Patent No. 1,410,524, granted March 21, 1922, upon the application of Dorsey F. Asbury, of Washington, District of Columbia, for an improvement in "Breech Closures," an error appears in the printed specification requiring correction as follows: Page 4, line 126, claim 25, for the word "removed" read *moved*; and that the said Letters Patent should be read with this correction therein that the same may conform to the record of the case in the Patent Office.

Signed and sealed this 17th day of April, A. D., 1922.

[SEAL.]

KARL FENNING,

Acting Commissioner of Patents.
